FENCE CHARGING DEVICE

Charles Gallot and Albert Alpaugh, Milwaukee,
Wis.

Application May 6, 1940, Serial No. 333,691

6 Claims. (Cl. 175—373)

This invention relates primarily to a charging device for electric fences, although certain features thereof are also applicable to other uses.

This application is a continuation in part of our co-pending application, Serial No. 152,704, filed July 9, 1937, now Patent #2,202,691.

In the application above identified, there is disclosed a fence charging device capable of giving to a fence brief high potential electric charges, recurring at spaced intervals, which render the fence effective as an animal barrier without danger of electrocution. The timing of the charges is accomplished by a ball which, travelling down a raceway, closes the switch of an electromagnetic device, which thereupon drives the ball back up the incline again and briefly charges the fence. The arrangement is such that should operation cease from any cause, the device will come to rest with all the switches in open position, so that no charge other than the brief one of normal operation can be delivered to the fence.

Although the device of the former application can be restarted from a rest position by manual operation of the ball, yet this is inconvenient and involves danger of interference with the working of the device. One object of the present invention therefore is to provide a self-starting switch for such a device.

Another object is to interrelate the operation of such a self-starting switch, with the other circuits of the device, in such manner as to eliminate the possibility of prolonged charging of the fence.

Another object is to interrelate the electric circuits with an "on-and-off" switch in such manner that the device will start operation automatically upon throwing of the switch to the "on" position.

Other objects and advantages will appear, expressed or implied, from the following description of an electric charging device embodying the present invention.

Figure 1 is a diagrammatic view of an electric fence charger having a simple self-starting switch device incorporated therein.

Fig. 2 is a partial diagrammatic view of a modification of the device of Fig. 1, in which the self-starting switch is combined with an on-and-off switch, for automatic starting.

Fig. 3 is a diagrammatic view of another modification of the device, in which the starting switch also controls the fence circuit, to positively prevent charging of the fence excepting during normal operation of the device.

The fence charger illustrated in Fig. 1 is controlled by a ball 10 rolling up and down an inclined track 11 and 12. The ball is driven up the track by the power stroke of a lever 13, pivoted at 14 and carrying a rubber driving head 15 in position to strike the ball 10. The lever 13 is normally retained in retracted position against a stop screw 16 by a spring 17, but may be actuated by an electromagnet 18 to drive the ball 10 along its track. Power from a battery 19 energizes the magnet by means of a circuit 20. A contact 21 is mounted upon the lever 13, and a second contact 22 is carried by a resilient arm 23 likewise mounted on the lever 13. The arm 23 is positioned in the path of the ball 10 so that impact of the ball thereagainst closes the electromagnet circuit through the contacts and causes the lever 13 to drive the ball upwardly again. As the ball leaves the arm 23, the contacts are opened and the levers resume their positions of rest.

The arm 23 is of such stiffness that the weight of the ball 10 at rest against the arm will be insufficient to close the contacts 21 and 22, a positive impact of the ball being required for this purpose. For this reason, the circuit will always be open when the device is at rest.

To effect starting, provision is made for causing the lever 13 to execute an initial power stroke, and, for this purpose, an auxiliary hand switch 24 is connected across the circuit in parallel with the switch 21—22, the closing of which will of course energize the electromagnet 18 and cause the lever 13 to execute a driving stroke. The switch 24 is preferably biased toward open position by gravity or otherwise, so as to render it ineffective at the moment it is released.

The device thus far described has, among other uses, been found useful for delivering an instantaneous high frequency charge to an electric fence. For this purpose the fence (not shown) is connected to the high potential secondary 25 of a transformer through a fence circuit 26. The low potential primary coil 27 of the transformer is energized from the battery 19 through a circuit 28, a switch 29 being available to cut out a portion 27' of the primary coil through a lead 30.

The circuit 28 is controlled by a novel switch described in the application above identified. It includes a contact 31 carried by an arm 32 mounted upon the lever 13 to swing therewith, and a second contact 34 carried by an arm 35 fastened to a stationary support 36. Upon delivery of a power stroke by the lever 13 in the manner previously described, the contact 31 will, at the end

of the stroke, strike the contact 34, thus causing delivery of a momentary charge to the fence circuit 26.

The self-starting switch 24 in the embodiment of the device described above, is simple and effective for the purpose, but in some cases may be disadvantageous due to the fact that if the switch is held closed, lever 13 may be held by the magnet in its advanced position until the ball 10 has completed its return stroke, whereupon the ball and the system would remain mechanically at rest. This difficulty is avoided with a switch of the type shown in Fig. 2, in which the self-starting switch is combined with a circuit opening switch in a simple automatic start-and-stop mechanism. In this form of device, the electromagnet 18 is connected to the circuit contacts 21 and 22 through a switch arm 24' and a switch contact 20' in the circuit 20. When the switch arm is dropped to the "off" position shown in dotted lines, circuit 20 is completely broken and the device will come to rest. Automatic self-starting is provided by a contact 37 which the switch arm 24' must pass in returning to the "on" position, the contact 37 being arranged to short the circuit 20 across the contacts 21 and 22 upon contact with the switch arm 24'.

In order to prevent lengthy energization of the fence circuit 26 by protracted closing of the starting switch, the device of Fig. 2 has been arranged so that the switch arm 24 never comes to rest on the contact 37, but merely wipes across the contact in crossing from the open to the closed position. Several types of switches may be used for this purpose, but a simple toggle switch, as shown in the drawings is satisfactory. An operating lever 38 is pivoted adjacent to the switch arm 24' but for movement independently thereof, and the two arms are connected by a spring 39. When movement of the lever 38 moves the spring 39 past the center of the switch arm 24', the switch arm will be snapped into the opposite position. This allows only momentary closing of the circuit through the contact 37 and prevents a continuous or prolonged charge in the fence circuit 26.

The form of device shown in Fig. 3 is generally similar to that in Figs. 1 and 2, but the circuits have been rearranged somewhat so that the transformer circuit itself passes through the starting switch. The switch is of the same type as that disclosed in Fig. 2, including an operating lever 38 and a spring 39 by means of which the switch arm 40 is snapped from open to closed position and reverse. A wire 41 connects the switch to the battery 19. During normal operation with the switch in the "on" position, the wide head 42 of the switch arm 40 engages a contact 43 electrically connected to the arm 23, so that closing of the contacts 21 and 22 by the ball 10 will permit energization of the magnet 18. At the same time, however, with the switch arm 40 in the "on" position the broad head 42 also engages contact 44, connected through wire 45 to contact 31 so that closing of the contacts 31 and 34 by movement of the lever 13 will permit energization of the coil 27 and thereby charge the fence circuit 26.

When the switch 40 is snapped to the "off" position, both the electromagnet circuit 20 and the transformer coil circuit 28 will be positively broken. As the switch arm 40 snaps back to the "on" position, the head 42 will wipe across the contact 37, as in the device shown in Fig. 2, thus energizing the magnet 18, and causing the lever 13 to deliver the initial power stroke to the ball 70

10. It may be noted, however, that the transformer circuit through the contact 34 can never be energized at the same time as the energization of the electromagnet through the contact 37 so that even if for any reason the switch should stick or be delayed in its passage across the contact 37, and the contacts 31 and 34 be thereby held in closed position by the magnet, nevertheless no energization of the fence charging transformer coil is possible in such position.

Various changes may be made in the embodiment of the invention above specifically described without departing from or sacrificing the advantages of the invention as defined in the appended claims.

We claim:

1. In a charger for an electric circuit, the combination of a reciprocable member, a striker for successively driving said member in one direction, 20 means including a normally open switch closable by successive movements of said member in an opposite direction for actuating said striker, and means for causing said striker to execute an initial power stroke.

2. In an electric controller the combination with an electric circuit of circuit closing means, control means intermittently operating said circuit closing means, impelling means controlled by the closing of the circuit for actuating the control means, and auxiliary closing means for closing the circuit while said first named closing means remains open to thereby cause said impelling means to execute an initial power stroke.

3. In a device of the character described, the combination of a reciprocable member, an inclined guide therefor, a driver disposed adjacent the lower end of said guide for driving said member upward along said guide, an electromagnet for actuating said driver, switch means non-responsive to the static weight of said member and actuated by impact of said member thereagainst for energizing said electromagnet, and additional switch means for energizing said electromagnet independently of said first named switch means.

4. In a device of the character described, the combination of an electromagnet, switch means for actuating said magnet, control means intermittently closing said switch, said switch being normally open but being closable by impact of said control means, an impeller for said control means actuated by said magnet, an additional means for actuating said magnet independently of said switch means, said additional means including an electric contact and a snap switch member separated from said contact in all positions of rest, but momentarily engaging said contact in passing from one rest position to another.

5. In a device of the character described, the combination of an electromagnet, switch means for closing an electric circuit through said electromagnet, control means intermittently closing said switch, said switch being normally open but being closable by impact of said control means, an impeller for said control means actuated by said magnet, a second switch for opening said circuit to thereby prevent actuation of said magnet by said first named switch, and a contact unengaged by said second switch in either open or closed position thereof, but being engaged by said second switch in passing from open to closed position to thereby establish an electric circuit through said magnet independently of said first named switch.

6. In an intermittent charger, the combina-

tion of an intermittently recurring control member, an electromagnet circuit having a switch closable by impact of said control member, an electromagnet actuated by closing of said switch, an impeller for said control means actuated by said magnet, a work circuit, a switch in said work circuit closable by movement of said impeller, a main control switch having open and closed positions, said switch in the closed position establishing the electromagnet circuit through said first named switch means, said control switch in the closed position also establishing

said work circuit through said second named switch, starting means associated with said main control switch for establishing a circuit through said electromagnet independently of said first named switch means momentarily as said control switch passes from open to closed position, said last named means being unengaged by said control switch in either open or closed position and being inoperable in all positions of said control switch in which said work circuit is closed.

CHARLES GALLOT.
